UNITED STATES PATENT OFFICE.

RUDOLPH A. KUEVER, OF IOWA CITY, IOWA, ASSIGNOR TO THE PEPSODENT COMPANY,
OF CHICAGO, ILLINOIS, A CORPORATION OF ILLINOIS.

DENTIFRICE.

No Drawing.

Application filed March 8, 1922. Serial No. 542,135.

To all whom it may concern:

Be it known that I, RUDOLPH A. KUEVER, a citizen of the United States, and a resident of Iowa City, in the county of Johnson and State of Iowa, have invented certain new and useful Improvements in Dentifrices, of which the following is a specification.

This invention relates to dentifrice, and it is the object thereof to produce a dentifrice of superior efficiency and beneficial action in the mouth.

The invention has for its object to obtain the maximum benefit in the operation of a dentifrice from two standpoints—both the chemical action and mechanical action.

It is now well recognized by modern specialists that an acid dentifrice, provided the acidity is innocuous to the teeth, is advantageous in stimulating salivary flow and increasing alkalinity of the saliva. It is further well appreciated that alkaline dentifrices are not beneficial.

The mechanical action of a dentifrice is that of its polishing agent.

Following is a statement of the properties essential to the efficiency of a polishing agent and essential to its freedom from injurious incidental effects:

(a) Inert; the polishing agent employed in the dentifrice should preferably be inert to acids, and not affected by the chemical reactions which take place when the dentifrice is used in the mouth. If the polishing agent is alkaline, it is impossible to produce an acid dentifrice, and all the advantages above referred to of such a dentifrice are at once sacrificed because the bulk of the polishing agent in a dentifrice is necessarily enough to counteract any practical acidity which may be employed therein.

(b) Solubility; one of the important sources of trouble due to the use of dentifrices containing polishing agents is the lodgment under the gum margins of particles of the polishing agent which accumulate and set up irritation and inflammation. This condition is the more serious as the gum margins are the more infected. In order to counteract this damaging effect, the polishing agent in the dentifrice should be soluble, so that particles thereof lodged under the gum margins will be dissolved by the water of the saliva within a comparatively short time after the teeth are brushed. On the other hand the polishing agent is employed

for that purpose and must stand up to that duty; it is of no utility to provide an immediately soluble substance (such for instance as sugar of milk) which will not retain its solid form long enough to serve efficiently as a polishing agent.

Solubility is expressed customarily by chemists in terms of the number of parts of water in which one part of the substance in question will dissolve completely at room temperature. Thus a substance having a solubility of 1 in 1000 is a substance, one part of which will be completely dissolved in one thousand parts of water and has a very low solubility as compared with a solubility of 1 in 50. I have determined that the solubility of the polishing agent should be less than 1 in 200. In other words it should require more than two hundred parts of water to dissolve one part of the polishing agent, and a very satisfactory solubility would be approximately 1 in 500. This solubility would insure that the polishing agent would stand up to its duty but lodged particles thereof would be dissolved within a short time after the teeth were brushed.

(c) Hardness: The next point to be considered in connection with the polishing agent is of course its hardness. A polishing agent should be hard enough to serve efficiently for that purpose, but should not be hard enough to cut the teeth, even though the teeth be violently scrubbed therewith. Hardness is expressed by a scale well known to chemists. The hardness of tooth substance, including dentine cementum and enamel, ranges from 3.5 to 7. The average enamel is 5.5 to 6 in hardness. I have determined as a preferable range of hardness for the polishing agent in a dentifrice a figure less than 3.5 and greater than 1.

The dentifrice of my invention therefore may be defined as one wherein a polishing agent is employed which is inert to acid, and therefore may be used in an acid dentifrice; inert to the chemical reactions taking place in the mouth; has a solubility less than 1 in 200, but nevertheless is soluble enough so that particles thereof will not lodge and remain under the gum margins; and has a hardness less than 3.5 and greater than 1.

As an embodiment of the invention in more specific form, I have discovered that anhydrous calcium sulphate as a dental polishing agent possesses the combination of

properties which make it of exceedingly superior utility as a polishing agent for a dentifrice.

As a preferable embodiment of the invention, I combine anhydrous calcium sulphate with an acid. The combination produces an acid dentifrice having all the advantages thereof and the polishing agent in the combination has each of the properties above described. Thus anhydrous calcium sulphate is (1) inert to the acid and to the chemical reactions of the mouth. (2) Its solubility is 1 in 500, i. e., it will stand up during the tooth brushing operation but will dissolve within a short time from under the gum margins. (3) Its hardness is 1.7 which is hard enough to make it a good polishing agent but too soft to cut the teeth.

An illustrative formula for a dentifrice of my invention in an acid form and embodying the new polishing agent in an efficient combination, would be as follows:

	Parts.
Anhydrous calcium sulphate	100
Gums	3
Organic acids or acid salts	10
Glycerine	40
Water	40
Flavoring.	

Of course these proportions may be varied within wide limits.

In the use of the foregoing dentifrice, the mechanical action of the dentifrice is exceedingly efficient but not destructive to tooth structure, salivary stimulation is produced, alkalinity of the saliva is increased, by chemical reactions to which the polishing agent forming the body of the dentifrice is inert, and the salivary flow stimulated by the acid reaction of the dentifrice dissolves any particles of the polishing agent lodged under gum margins, in a short time after the teeth are brushed.

Having described my invention, I claim:

1. A dentifrice comprising anhydrous calcium sulphate mixed with suitable binder and flavoring ingredients.

2. A polishing agent for a dentifrice, consisting of anhydrous calcium sulphate.

3. A dentifrice comprising anhydrous calcium sulphate, glycerine and flavoring.

4. An acid dentifrice comprising anhydrous calcium sulphate and an acid ingredient.

In witness whereof, I hereunto subscribe my name this 3rd day of March, A. D. 1922.

RUDOLPH A. KUEVER.
